UNITED STATES PATENT OFFICE

100,740

DESIGN FOR A CAP

Jean Sénégas, New York, N. Y.

Application November 21, 1935, Serial No. 59,684

Term of patent 3½ years

To all whom it may concern:

Be it known that I, Jean Sénégas, a citizen of the United States of America, residing in New York city, county of New York, Borough of Manhattan and State of New York, have invented a new, original, and ornamental Design for a Cap, of which the following is a specification, reference being had to the accompanying drawing, forming a part thereof:

The figure is a perspective view of a cap showing my design.

The side of the cap opposite to that shown does

not have the special ornamentation which is shown as provided by the arrangement of the diagonal band of stripes which transversely overlies the conventional representation of cartridges, the appearance presented by this opposite side being in other respects similar to that shown in the drawing.

I claim:

The ornamental design for a cap, as shown and described.

JEAN SÉNÉGAS.
